UNITED STATES PATENT OFFICE.

EDGAR B. NICHOLS, OF ROCHESTER, NEW YORK, ASSIGNOR TO THE PFAUDLER COMPANY, OF ROCHESTER, NEW YORK, A CORPORATION OF NEW YORK.

CENTRIFUGAL AGITATOR AND PROCESS OF MAKING THE SAME.

Application filed July 23, 1923. Serial No. 653,153.

To all whom it may concern:

Be it known that I, EDGAR B. NICHOLS, a citizen of the United States, residing at Rochester, in the county of Monroe and 5 State of New York, have invented certain new and useful Improvements in Centrifugal Agitators and Processes of Making the Same; and I do hereby declare the following to be a full, clear, and exact description 10 of the same, reference being had to the accompanying drawings, forming a part of this specification, and to the reference numerals marked thereon.

This invention relates to agitators of the 15 variety adapted to be rotated in a container for stirring the contents thereof and operating by a centrifugal form of action, one object of the invention being to provide an efficient agitator of this character capable 20 of being produced by practical manufacturing methods with economy of materials and labor. Another object is the provision of such a device adapted to be constructed from blanks of sheet metal advantageously formed 25 and united to produce an agitator requiring but little metal material while having an integral and strong type of construction. Still a further object is to provide an agitator of the above character particularly 30 adapted for having a coating of glass or other vitreous material efficiently fused or baked over its exterior to protect the same. A further object of the invention is to provide an improved method of constructing 35 hollow agitators from sheet material to afford one having walls of substantially uniform thickness throughout and of relatively light weight.

To these and other ends the invention re- 40 sides in certain improvements and combinations of parts all as will be hereinafter more fully described, the novel features being pointed out in the claims at the end of the specification.

45 In the drawings:

Fig. 1 is a side view of an agitator embodying the present invention.

Fig. 2 is an end view of the same.

Fig. 3 is a sectional view on line 3^a—3^a in 50 Fig. 2.

Fig. 4 is a detail sectional view on the line 4^a—4^a, Fig. 1 and

Fig. 5 is a sectional view on the line 5^a—5^a in Fig. 2.

Similar reference numerals throughout 55 the several views indicate the same parts.

The present embodiment of the invention comprises an agitator formed from a pair of sheet metal blanks cut, shaped and united to provide a closed hollow body of efficient 60 agitating or impelling shape. This form of construction not only affords substantial economy in materials and the cost of manufacture, as compared with a cast metal or other solid construction, but also facilitates 65 the production of efficient agitating shapes or designs and likewise affords a form of construction efficiently adapted for the application thereto by a fusing or baking process of a coating of glass or other vitreous 70 material having the chemically resistant, durable and sanitary qualities well recognized in the art.

Referring more particularly to the drawings, the present construction is shown as 75 combining a pair of sheet metal blanks 10 and 11, each of which is initially cut to produce a central hub portion 12 with circumferentially spaced blades 13 extending outwardly therefrom with a rearwardly inclined curvature, as shown in Fig. 2. Four such blades are employed in the present instance, but of course, this number may be varied and other forms of curvature in planes transverse to the axis of rotation may obviously be substituted; that shown in the present instance having however, been found effective for the purposes desired. Marginal portions or flanges 14 of substantial 80 depth are then formed or turned angularly in directions parallel with the axis of rotation as best shown in Fig. 5. These marginal portions of the two blanks extend toward each other and meet preferably in the abutting relation shown at 15, thus providing centrifugally impelling surfaces of substantial width in directions parallel with the axis of rotation.

The marginal edges of the blanks brought together as described above are preferably 100 united by welding, brazing or the like as indicated at 16, Fig. 5. The marginal portions 14 preferably extend continuously from the rear side of one blade adjacent the hub along the forward side of the succeeding blade, but the margins of the forward and rear side of each blade are preferably 105 discontinuous at the tip, being brought to-

gether by the forming process described and also welded or brazed as at 17. It is obvious, of course, that one of the blanks may be formed as described and united with a plane 5 shaped blank having the angularly turned margins omitted, where a vane of less width of impelling surface is desired.

For attaching the agitator to a supporting and driving shaft, the hub of the rear blank 10 11 preferably has an opening 18 formed centrally therein with its periphery swaged outwardly to produce a sleeve 19 as shown in Fig. 3, affording a substantial shaft bearing. The opening 18 communicating between the exterior and all portions of the interior of the body serves an additional purpose hereafter described. It is preferred also to form a forwardly extending boss 20 centrally of the hub of blank 10 to facilitate 20 the flow of the agitated material, as well understood in the art.

There is thus produced a hollow, closed, sheet metal body of an integral and rigid nature, the strength of which may be varied 25 by varying the thickness of the sheet metal employed. The blanks may be accurately cut, formed up and united according to various efficient shapes and designs by practical manufacturing methods with substantial 30 economy over a cast metal or other solid construction, especially where it is desired to employ a non-corrosive and relatively expensive metal. An important feature of the present invention, however, resides in the 35 fact that the construction described is particularly adapted for producing a metal body capable of having a protective coating of glass or other vitreous material as indicated on an exaggerated scale at 21, Fig. 5, fused or baked on its outer surfaces. This 40 advantage accrues primarily from the provision of walls of uniform thickness or mass and a body shape the portions of which are hollow and in communication with each 45 other and the exterior through the shaft opening 18, for equalizing temperature conditions and gaseous pressures generated by a heating process such as required to fuse the enamel. In this construction steel or 50 other suitable sheet metal may be used and the invention thus supplies a light, strong and economical metal agitator of efficient design with an unbroken surface coating of fused vitreous material having the chemically 55 resistant, durable and sanitary qualities well known in the art.

I claim as my invention:

1. A centrifugal type agitator comprising a pair of sheet metal blanks shaped to 60 provide central hub portions with circumferentially spaced blades, one of said blanks having a peripheral margin of substantial depth formed angularly toward the other blank and welded thereto to provide im-

pelling vanes of substantial width transverse to the direction of rotation. 65

2. A centrifugal type agitator comprising a pair of sheet metal blanks shaped to provide central hub portions with circumferentially spaced blades one of said blanks 70 having a peripheral margin of substantial depth formed angularly toward the other blank and welded thereto to provide impelling vanes of substantial width transverse to the direction of rotation, and one 75 of said blank hubs having a shaft receiving opening formed therein, communicating with the interior of the agitator and a fused coating of vitreous material protecting the exterior surface of the agitator. 80

3. A centrifugal type agitator comprising a pair of sheet metal blanks cut and formed to provide central hub portions having circumferentially spaced blade portions extending transversely of the axis of rotation with marginal portions of said blanks turned angularly toward each other and welded together to provide impelling vanes of substantial width in a direction parallel 85 with said axis. 90

4. A centrifugal type agitator comprising a pair of sheet metal blanks cut and formed to provide central hub portions having circumferentially spaced blade portions extending outwardly in rearwardly inclined 95 curves with marginal portions of said blanks of substantial depth turned toward each other and welded together to provide impelling vanes of substantial width in a direction parallel with the axis of rotation, 100 one of said blank hubs having a shaft receiving opening communicating with the agitator interior, and a fused coating of vitreous material protecting the exterior surfaces of the agitator. 105

5. A centrifugal type agitator comprising a pair of sheet metal blanks cut and formed to provide central hub portions having circumferentially spaced blade portions extending outwardly in rearwardly inclined 110 curves with marginal portions of said blanks of substantial depth turned toward each other and welded together to provide impelling vanes of substantial width in a direction parallel with the axis of rotation, 115 said marginal portions on the forward and rear sides of each blade being welded together at the blade tip to close the agitator body and one of said hubs having a central opening therein communicating with the 120 agitator interior and formed with a peripheral flange for receiving a shaft, and a fused enamel coating protecting the agitator exterior. 125

6. The method of constructing a hollow agitator which comprises shaping from sheet material two separate sections to provide each with a body portion having a plu-

rality of spaced radiating portions, forming an angularly disposed peripheral margin upon each of said sections and superimposing the sections and uniting the edges of 5 said marginal portions by welding.

7. The method of constructing a hollow agitator which comprises shaping from sheet material two separate sections to provide each with a body portion having a plurality of tapered radiating portions, forming angular portions upon each of said sections and bending the edges of said body portions and the longitudinal edges of said tapered radiating portions, superimposing 10 the sections so that the aforesaid edges of one section substantially meet the corresponding edges of the other section, uniting said sections by welding said edges, and also uniting the extremities of said angular portions by welding so as to close the ends of 15 the tapered radiating portions.

8. The method of constructing a hollow

agitator which comprises shaping from sheet material two separate sections to provide each with a body portion having a plurality of spaced radiating portions, forming an angularly disposed peripheral margin upon one of said sections, uniting the edge of said margin with the other of said sections by welding, and fusing an enamel coating upon the exterior of the united sections. 25

9. The method of constructing a hollow agitator which comprises shaping from sheet material two separate sections to provide each with a body portion having a plurality of spaced radiating portions, forming an angularly disposed peripheral margin upon each of said sections, superimposing the sections and uniting the edges of said marginal portions by welding and fusing an 30 40 enamel coating upon the exterior of the united sections. 35

EDGAR B. NICHOLS.
